(57) **CLAIM**

The ornamental design for a three bar access control gate with color authentication, as shown and described.

DESCRIPTION

The patent file contains at least one drawing executed in color. Copies of this patent with color drawing(s) will be provided by the office upon request and payment of the necessary fee.

Figure 2.1 is a perspective view of a three-bar access control gate showing the new design in a first configuration with no color authentication;

Figure 2.2 is a top view thereof;

Figure 2.3 is a left side view thereof (the right side view being a mirror image thereof);

Figure 3.1 is a rear view thereof;

Figure 3.2 is a front view thereof;

Figure 4.1 is a perspective view of the three-bar access control gate in a second configuration with a red color authentication;

Figure 4.2 is a top view thereof;

Figure 4.3 is a left side view thereof (the right side view being a mirror image thereof);

Figure 5.1 is a rear view thereof;

Figure 5.2 is a front view thereof;

Figure 6.1 is a perspective view of the three-bar access control gate in a third configuration with a green color authentication;

Figure 6.2 is a top view thereof;

Figure 6.3 is a left side view thereof (the right side view being a mirror image thereof);

Figure 7.1 is a rear view thereof; and,

Figure 7.2 is a front view thereof.
